UNITED STATES PATENT OFFICE.

JAY B. RHODES, OF CHICAGO, ILLINOIS, ASSIGNOR TO GEORGE E. GUERNE,
OF SANTA ROSA, CALIFORNIA.

DESIGN FOR A PUMP-CASING.

SPECIFICATION forming part of Design No. 31,561, dated September 26, 1899.

Application filed December 9, 1897. Serial No. 661,324. Term of patent 14 years.

To all whom it may concern:

Be it known that I, JAY B. RHODES, a citizen of the United States, residing at the city of Chicago, in the county of Cook and State 5 of Illinois, have invented a certain new and useful Design for a Pump-Casing, of which the following is a specification.

This invention relates to a new and original design for pump-casings.

10 The design is fully illustrated in the accompanying drawings, forming a part of this specification, in which—

Figure 1 is a side elevation of a pump-casing, showing my new design. Fig. 2 is a front elevation or an elevation taken from the right 15 of Fig. 1 of a pump-casing, showing my new design.

As shown in the drawings, the leading fea-

tures of my new design consist of double convex plates placed facing each other, and the 20 edges of the oppositely-facing plates are secured together by suitable bolts or other means, as illustrated, and the whole is supported by a suitable base.

Having thus described my invention, what 25 I claim as new, and desire to secure by Letters Patent, is—

The design for a pump-casing as herein described and shown.

In witness whereof I have hereunto set my 30 hand and seal in the presence of two witnesses.

JAY B. RHODES. [I. S.]

Witnesses:

OTIS A. EARL,
A. A. GUERNE.
